United States Patent Office

Des. 219,823
Patented Feb. 2, 1971

219,823

GAME BOARD

Joseph Imperato, Selden, N.Y., assignor to Riders Up,
Inc., Selden, N.Y.

Filed Aug. 11, 1969, Ser. No. 18,627

Term of patent 14 years

Int. Cl. D21—01

U.S. Cl. D34—5

FIG. 1 is a perspective view of the game board;
FIG. 2 is a right side elevational view of the game
board;

FIG. 3 is a front elevational view of the game board;
and

FIG. 4 is a rear view of the game board.

The base, not shown, is planar and the side opposite
that shown is substantially the same as the side which
is shown.

I claim:

The ornamental design for a game board, substantially
as shown and described.
